UNITED STATES PATENT OFFICE.

STERLING H. CAMPBELL, OF ST. LOUIS, MISSOURI, ASSIGNOR TO WESTERN RAILWAY EQUIPMENT COMPANY, OF ST. LOUIS, MISSOURI, A CORPORATION OF MISSOURI.

RETAINING-VALVE FASTENING.

Application filed April 14, 1927. Serial No. 183,641.

My invention relates to retaining valve fastening means and its object is to reduce such fastening means to the most simple form possible and at the same time to secure the necessary vertical adjustment of the valve to compensate for variation in the length of the valve pipe. This I accomplish, in the preferred form of my device, by providing the valve with a pair of integral lugs, each having a vertical slot cooperating with a stud permanently carried by the wall of the car to which the valve is attached.

In the accompanying drawings, which illustrate one form of retaining valve fastening made in accordance with my invention, Figure 1 is a front elevation; Figure 2 is a side view; and Figure 3 is a top plan view.

The body of the valve, indicated at 5, is provided at each side with an integral lug 6 in which is formed a vertical slot 7. Passing through the end wall 8 of the car adjacent to each slot is the short end of a stud 9 divided into two parts by a collar 10. The projecting portion of this short end is riveted over to form a head 11, thus securing the stud in position on the car. This method of applying the stud not only insures its permanent retention on the car but also effectively prevents its rotation when the nut, hereinafter referred to, is applied. After passing through the slots 7 in the lugs 6 the long ends of the studs are engaged by nuts 12 which secure the valve firmly in position. The slots 7 permit of the necessary vertical adjustment of the valve to compensate for variations in the length of the valve pipe 13. In order to lock the nuts against accidental removal, I prefer to provide the ends of the

studs with slits 14 so that the said ends may be spread by the insertion of a suitable tool 40 in said slits.

Having fully described my invention, what I claim as new and desire to secure by Letters Patent of the United States is:

1. A retaining valve having an integral part carried thereby and provided with a vertical slot, in combination with a bolt carried by a car and projecting through the slot to adjustably secure the valve in position on the car. 45

2. A retaining valve having an integral part provided with a slot, in combination with retaining means carried by a car and engaging with said slot to adjustably secure the valve in position on the car. 50

3. A retaining valve having a lug provided with a slot, in combination with a stud permanently secured to a car and projecting therefrom through said slot to adjustably secure the valve in position on the car. 55

4. A retaining valve having a pair of lugs each provided with a slot, in combination with a pair of studs permanently carried by a car and engaging with the slots to adjustably secure the valve to the car. 60

5. A retaining valve having a vertical body and provided with a pair of integral lugs projecting from the upper rear part of the body at opposite sides thereof, said lugs being provided with vertical slots, in combination with a pair of studs permanently carried by a car and engaging with the slots to adjustably secure the valve to the car. 70

In testimony whereof, I hereunto affix my signature, this 11th day of April, 1927.

STERLING H. CAMPBELL.
